WELL PIPE PLUG

Frederick Stone, Torrance, and Granville S. Knox, Los Angeles, Calif., assignors to Hydril Company, Los Angeles, Calif., a corporation of California

Application May 23, 1936, Serial No. 81,466

30 Claims. (Cl. 166—13)

This invention has to do with plugs for closing well pipes below the ground surface against the upward flow of well fluid, and while certain features of the invention are applicable to such plugs generally, the invention is primarily concerned with an improved type of plug adapted to be forced down within the drill string to facilitate its removal after the occurrence of a twist-off. Accordingly, the invention will be described with 10 that main objective in view.

Occasionally during well drilling operations, the drill string, comprising successive lengths of pipe connected by couplings, becomes severed as a result of torsional or other strains, so that 15 it is necessary to remove the upper severed section from the well and to then recover the lower section. In case the well is flowing gas or liquid, the upper severed section of the drill string is customarily pulled through a packing head on 20 the casing that holds the well pressure and prevents fluid leakage around the drill pipe. One of the major objects of the invention is to keep the drill pipe closed against the escape of well fluid therethrough as the pipe is being pulled, by 25 the use of an improved type of plug which is pumped or otherwise moved down within the pipe and finally positioned to close the pipe at or near 30 its lower end. In its preferred form, the plug comprises expandable packer and pipe engaging means, both of which are maintained in radially contracted condition as the plug is being pumped 35 downwardly through the pipe, and which are releasable to seal off around the plug and to hold it against subsequent longitudinal movement in 40 the pipe. One of the principal features of the invention is the provision of a control device whereby the packer and pipe engaging means are automatically caused to expand by virtue of 45 movement of a portion of the plug out of the lower open end of the pipe.

Preferably we provide in the plug a pipe engaging means adapted to arrest plug movement by engagement with an internal shoulder of a flush joint type drill pipe, and in a position such that when set, the packer will be positioned in a reduced diameter coupling bore. In this manner, we are able to avoid having to expand the packer 50 to an extent greater than the minimum internal diameter of the drill string, and yet maintain a fluid-tight closure. As will later appear, the plug has certain dimensional characteristics relative 55 to the pipe stand lengths, that will insure final positioning of the plug at predetermined locations relative to the lower end of the drill pipe.

The invention embodies numerous additional objects and aspects, but all these as well as the features referred to above will be better understood from the following detailed description of 60 the invention in one of its typical and preferred

forms. Throughout the description, reference is had to the accompanying drawings, in which:

Fig. 1 is a general view, partly in section, showing the plug positioned above the kelly cock and before being released to be pumped down through 5 the drill string;

Fig. 2 is a view similar to Fig. 1 showing the plug released for passage down through the drill string and with the adapter sleeve in engagement 10 with the top pipe coupling;

Fig. 3 is an enlarged fragmentary sectional view 15 illustrating the positions of the latch arms as the plug is being forced downwardly through the adapter sleeve;

Figs. 4, 5, 6, and 7 are longitudinal sectional 20 views, continuing in downward progression in the order named, showing the plug parts in set position with the latch arms confined by the adapter sleeve;

Figs. 8, 9, 10 and 11 are sectional views similar 25 respectively to Figs. 4, 5, 6 and 7, showing the plug parts in released positions with the packer radially expanded and the pipe gripping means projected radially into the engagement with a coupling shoulder;

Figs. 12 and 13 are vertically continuing views 30 showing the drill pipe in section and the plug in elevation, with its lower end projecting out the lower end of the upper severed section of the drill string;

Figs. 14 and 15 are enlarged cross sections on 35 lines 14—14 and 15—15 of Figs. 5 and 9, respectively, showing the pipe engaging balls in radially contracted and expanded positions;

Fig. 16 is an enlarged cross section on line 40 16—16 of Fig. 6; and

Fig. 17 is an enlarged cross section taken on line 45 17—17 of Fig. 7 through the latch arm pivots.

In the drawings we have shown a typical and preferred form of plug, generally indicated at 20 40 (see Figs. 1, 2, 12 and 13), whose normal diameter is sufficiently small to enable the plug to pass freely down through the drill string 21. The latter is shown typically to be made up of pipe lengths 22 connected by external flush joint couplings 23, 45 the threaded box ends of the pipe having internal upsets 24 beyond the coupling pin ends 25 which present internal annular shoulders 26 adjacent the pipe upsets. In the specific form of the invention shown, the pipe engaging means carried 50 by the plug is particularly adapted for engagement, when released, with the coupling shoulders 26 to prevent longitudinal movement of the plug within the drill string, and while this type of pipe engaging means is preferred, it is to be understood 55 that the invention is not necessarily limited thereto. For reasons that will later appear, the length of the plug 20 has a predetermined relationship to the length of a complete pipe stand comprising one pipe length 22 and a single cou- 60

pling 23. As best illustrated in Figs. 12 and 13, the plug length is in excess of the length of a standard single pipe stand for example, assuming the pipe stand to be around twenty-eight to thirty feet long, the plug length preferably will be greater by at least five or six feet in order to insure that regardless of where the twist-off may occur, the plug will be finally positioned in the desired predetermined position within the pipe above. Incidentally it may be mentioned that ordinarily the twist-offs will occur at points 27 at which the pipe upsets reduce down to the normal thickness of the pipe.

Referring now to Figs. 4 to 7, the plug 20 may be generally described as comprising a tubular body 28 including a series of pipe sections 29 connected by couplings 30, the number of these pipe sections and couplings intermediate the uppermost coupling 30a and the lowermost section 29a being determined by the desired length of the plug. For convenience of illustration, Fig. 5 has been broken at 31, with the understanding that between the portions of the plug above and below the break will be included a number of additional sections 29 and couplings 30. The plug comprises an elongated and radially expandable packer 32 carried on head 33 extending above the upper end of the body 28, and movable longitudinally relative thereto the packer being maintained in radially constricted condition, as shown in Fig. 4, during downward passage of the plug through the drill string, and finally released for expansion into engagement with the pipe, see Fig. 8, by a spring actuated means generally indicated at 331. The latter is controlled by latch device 34, see Fig. 7, operating to release the packer by movement of the latch out of the lower end of the pipe. When the packer is released, upward movement of the plug within the pipe is arrested by a pipe engaging means generally indicated at 35, which also is actuated by the latch controlled device 331 as the plug is projected out of the lower end of the pipe.

Referring particularly to Fig. 4, the head 33 comprises an enlarged diameter upper end portion 33a having a tapered nose 36, an elongated and reduced diameter intermediate portion 33b which tapers down at 37 to a lower rod portion 33c slidably extending through the bore 38 of a packer constricting fitting 39 threaded into the upper end of the top body section 29. As will later appear, release of the packer for expansion within the pipe is controlled by relative longitudinal movement between the head and the upper counterbored end 47 of member 39. An elongated packer sleeve 40 of flexible and compressible material, preferably rubber, is formed about the head 33, the upper portion 40a of the packer being set within an annular undercut recess 41 in the head and vulcanized thereto. If desired, the packer may be strengthened by suitable reinforcing, as by means of fabric 42 embedded therein. The packer has a substantially uniform external diameter corresponding to or perhaps slightly greater than the outer diameter of the body 20 and top portion 33a of the head. The lower portion of the packer below recess 41 is slideable and compressible longitudinally of the head, and is shaped in conformity with the tapered surface 37 of the head and the reduced diameter portion 33c therebelow.

The lower end of the packer sleeve is annularly split as indicated at 44 to provide lips 45 and 46 adapted to be forced by upwardly applied fluid pressure, into fluid-tight engagement with the

drill pipe 21 and portion 33c of the head, respectively. Normally the lower lipped end of the packer is radially constricted and confined against expansion by an extension 47 on the upper end of member 39, having a tapered bore 48 and one or more openings at 49. The packer is held within bore 48 and prevented from accidental withdrawal, by means of a coil spring 50 confined between the lower pin end of fitting 39 and nut 51 on the lower end of portion 33c of the head depending within the body 28. Normally, nut 51 engages the upper end of coupling pin 52 to limit downward movement of the head relative to the body. Upward relative movement of the head is limited by the engagement of stop sleeve 53 with the lower end of pin 54, as shown in Fig. 9, after the lower end of the packer has been withdrawn from the tapered bore 48. Before the plug is put into the pipe string, the lower lip portions 45 and 46 are securely tucked within the tapered constrictor 37, in the condition shown in Fig. 4.

The packer releasing device 331 comprises an elongated rod assembly made up of sections 56 threadedly connected by coupling sleeves 57 engaged by lock nuts 58. Rod section 56a has a threaded connection at 59 with the upper end of a pair of rod lengths 60 connected at 61 and carrying two longitudinally spaced sets of circularly spaced lugs 62 engaged by coil springs 63 and 64, the upper spring being supported on the internal body flange 65 and the lower spring on the upper end of pin 66. Springs 63 and 64 normally are compressed and the rod assembly releasably held in depressed position within the body, by the latch mechanism 34. The latter comprises a lower tubular body section 67 having intermediate its ends a pair of elongated and diametrically opposed slots 68, and closed at its lower end by a tapered nose 69 having a bore 70 normally closed by cap screw 71. Section 67 contains below slots 68 a rebound check device in the form of a tubular member 72 that is clamped between pin 73 and shoulder 74 by taking up the joint at 75, and having a pair of upwardly projecting spring fingers 76 that are normally spread to receive the lowermost rod section 77 in the position of Fig. 7. When the rod is raised, as will presently appear, spring fingers 76 move together in the position of Fig. 11 to prevent possible rebound of the rod to the point of again entering between the fingers.

Lower rod section 77 is connected at 78 with the rod length 60 above, and has a portion 77a of rectangular cross section within opposite sides of which are formed notches 79 which receive lugs 80 on a pair of latch arms 81 pivoted for vertical swinging movement on pins 82, see Fig. 17, terminating within body portion 67 at opposite sides of slot 68. When the plug is assembled for insertion within the drill string, latch arms 81 are held in the position of Fig. 7 to retain the rod assembly in set or depressed position, by an adapter sleeve 83 placed around the lower end of the plug and having at its upper end an angular surface shoulder 84 which is engaged by the notched portions 81a of the latch arms. The internal diameter of the adapter sleeve 83 is slightly larger than the plug outside diameter, so that when downward movement of the adapter is arrested under the conditions later explained, the plug will pass on down through it. At the same time, latch arms 81 will be moved inwardly by the constricting action of the adapter to permit passage of the plug, as shown in Fig. 3.

The pipe engaging means indicated at 35, comprises a plurality of circularly spaced openings 75

86, see Fig. 14, extending radially outward from the bore 87 of coupling 30a, and containing balls 88 adapted to be projected outwardly to the expanded position of Fig. 15, beyond which the balls are prevented from moving by slight constrictions 89 at the ends of openings 86. As the plug is being pumped down through the drill string, balls 88 assume the retracted positions of Figs. 5 and 14. When the rod assembly 33 is released by latch 34 for upward travel within the body, balls 88 are projected outwardly to their expanded positions by the action of rod extension 90 having a tapered cam surface 91 adapted, upon upward movement, to engage and spread the balls.

While the plug may be inserted within the drill string in any suitable manner, Figs. 1 and 2 will illustrate a typical sequence of operations for introducing the plug. In Fig. 2 the drill string 21 is shown to extend upwardly through a conventionally illustrated packing head 92 on the casing 93, and to be connected by coupling 94 with the usual kelly 95. The drill string is supported by slip bushings 96 within the diametrically illustrated table 97, and the upper end of the kelly carries the usual cock 98 below the swivel 99 through which circulating fluid is discharged downwardly through the pipe string, when cock 98 is open, from the rotary hose 100 via gooseneck 101 about the swivel.

In preparation for pumping the plug down through the drill string, the plug 20 is inserted through the swivel 99 and rested on top of cock 98 with the latter in closed position. A pipe 102, closed at its upper end by cap 103, is lowered over the plug and threaded at 104 into the upper end of the gooseneck. Cock 98 then is opened and circulating fluid pumped through line 100 to force the plug downwardly into the pipe string 21. As previously mentioned, the adapter sleeve 83 first will have been slipped over the lower end of the plug to hold the latch arms or dogs 81 in set position, and the bottom lipped end of the packing rubber tucked within the tapered bore 48 of the constricting member 47. If these preparations are not made, the plug will not pass through the tool joints of the pipe string. When the plug is forced down to the position of Fig. 2, adapter sleeve 83 is arrested by engagement with the internal shoulder 105 of coupling 94 as shown in Fig. 3. The plug however is forced down on down through the adapter, causing arms 81 to be swung inward and thereafter released within the drill pipe to the maximum outer positions (when between couplings) shown in dotted lines, but confined sufficiently while in the drill pipe, to hold the rod assembly in depressed position.

The plug is forced on down through the pipe until its lower end passes out the open end 106 of the pipe which, as shown in Fig. 13, is the location of the twist-off. The lower severed section of the drill string is indicated at 107. When the nose of the plug passes out of the end 106 of the pipe, latch arms 81 are thrown out of engagement with the latch rod, and swung outwardly and downwardly to the released positions of Fig. 11. Immediately upon release of the latch, springs 63 and 64 project the latch rod upwardly into engagement with balls 88, displacing them outwardly, see Figs. 8 to 11, and engaging the lower end of the head 33c to elevate it to the position of Fig. 8 and withdraw the packer from bore 48. In raising the head 33 relative to the body, springs 63 and 64 of course overcome the resistance of spring 50. Continued movement of

the plug out of the drill pipe is prevented by the engagement of balls 88 with coupling shoulder 26, which engagement is indicated at the ground surface by a quick rise in the circulating fluid pressure. The pumps then are quickly stopped and the circulating fluid pressure slowly released to allow a moderate upward flow of well fluid. This upward flow carries the plug upwardly to bring the packer within the bore of coupling 23a in a position predetermined by the engagement of balls 88 with the lower end of the coupling pin as shown in Figs. 8 and 9. The well pressure effectively expands the packer lip into fluid tight engagement with the coupling bore, preventing further upward flow of fluid.

Fig. 8 illustrates successive positions of the lower portion of the packer 40 during travel of the head 33 as it is projected upwardly by a rod assembly 331 when the latter is released by the latch. As will be understood from the foregoing, when first moved upwardly out of the constricting means 47, the packer 40 will be positioned within the relatively large diameter pipe bore below the coupling 23, in which position the lower lipped end of the packer will have expanded to substantially the dotted line position shown in Fig. 8. Then, as the packer is moved upwardly into the coupling bore 231, the packer is forced by the well fluid pressure into fluid-tight engagement with the coupling, the well pressure acting to force lip 45 outwardly against the coupling bore and to constrict lips 46 about portion 33c of the head, and also to longitudinally compress the lower portion of the packer, i. e., below recess 41, by upward movement relative to the mandrel portions 33b and 33c of the head. As the packer is forced upwardly relative to the mandrel it is expanded into tight engagement within the coupling bore, both by the inherent expansibility of the rubber upon compression, and by the effect of the mandrel taper 37 to spread the rubber.

By reference to Figs. 12 and 13 it will be seen that with the twist-off occurring directly below coupling 23b, the packer 32 will be set within the bore of coupling 23a spaced two pipe lengths above, with the balls 88 in engagement with the bottom shoulder of that coupling. As will be readily seen without the necessity for specific illustration, should the twist-off occur directly above the coupling (not shown) immediately below coupling 23b, then after the latch has been released and the plug moved upwardly by the well pressure, packer 32 will seat within and balls 88 engage the bottom end 26 of coupling 23.

For the purpose of resetting the plug, it is necessary to remove cap screw 71 in the nose of section 61, thread a resetting tool or rod into bore 110, see Fig. 11, and pull down the rod assembly until lugs 80 of the latch arms 81 reenter notches 79. Upon further downward movement of the resetting tool and rod assembly, the latch arms will fold inwardly into the body slots, and the adapter sleeve may then be slipped over the arms to retain them in the set position. After resetting, lip 45 of the packer is again tucked into counterbore 48 of the constricting member 47.

In the foregoing description, we have referred to the plug as being operated by movement out of the lower open end of a severed pipe. It will of course be understood that the utility and operativeness of the plug are not limited to situations where a pipe happens to be severed, as at a twist-off, and that the plug may be caused to operate automatically upon movement out of the lower end of any pipe below which there is sufficient

space for the latch arms 81 to swing outwardly to the extent of releasing the rod assembly.

We claim:

1. In a plug adapted to be moved downwardly through a well pipe, a packer adapted to be expanded radially into fluid tight engagement with said pipe, control means maintaining said packer in radially constricted condition during the downward passage of the plug in said pipe, the last mentioned means comprising a member movable vertically within the plug, a spring tending to move said member to cause the packer to expand within said pipe, and means for releasably holding said member against movement by the spring, the last mentioned means being releasable by movement of a lower portion of the plug out of the lower end of the pipe.
2. A plug adapted to be moved downwardly through a well pipe that is open at its lower end, said plug comprising radially movable means adapted to engage the inside of said pipe to hold the plug against upward movement therein, a member movable longitudinally within said plug to expand said pipe engaging means, a spring for so moving said member, means for releasably holding said member against movement by the spring, the last mentioned means comprising a latch operating by movement out of the lower end of said pipe to release said member for movement by said spring, and a packer having a depending lip portion expansible into tight engagement with the well pipe by upwardly applied fluid pressure.
3. In a plug adapted to be moved downwardly through a well pipe, a packer adapted to be expanded radially into fluid tight engagement with said pipe, control means maintaining said packer in radially constricted condition during downward passage of the plug in said pipe, radially movable means adapted to engage the inside of said pipe to hold the plug against upward movement therein, and means responsive to movement of a lower portion of said plug out of the lower end of the pipe, for actuating both said packer control means and pipe engaging means to expand them within said pipe at points spaced above its lower end.
4. In a plug adapted to be moved downwardly through a well pipe, a packer adapted to be expanded radially into fluid tight engagement with said pipe, control means maintaining said packer in a radially constricted condition during downward passage of the plug in said pipe, radially movable means adapted to engage the inside of said pipe to hold the plug against upward movement therein, and means responsive to movement of a lower portion of said plug out of the lower end of the pipe, for actuating both said packer control means and pipe engaging means to expand them within said pipe at points spaced above its lower end, the last mentioned means comprising a member movable vertically within the plug, a spring tending to move said member to cause the packer and pipe engaging means to expand within said pipe, and means for releasably holding said member against movement by the spring, the last mentioned means being releasable by movement of a lower portion of the plug out of the lower end of the pipe.
5. In a well pipe plug adapted to be forced downwardly through the pipe by fluid pressure, an elongated tubular body, a packer adapted to be radially expanded into fluid tight engagement with said pipe, means controlling the expansibility of said packer, pipe engaging means adapted to be moved radially outward relative to said

body, and an elongated rod movable longitudinally within said body to actuate both said packer control means and said pipe engaging means.

6. In a well pipe plug adapted to be forced downwardly through the pipe by fluid pressure, an elongated tubular body, a packer adapted to be radially expanded into fluid tight engagement with said pipe, means controlling the expansibility of said packer, pipe engaging means adapted to be moved radially outward relative to said body, and an elongated rod movable upwardly within said body from depressed to projected position to actuate both said packer control means and said pipe engaging means, a spring tending to thrust said rod upwardly, and means for releasably holding said rod in its depressed position.

7. In a well pipe plug adapted to be forced downwardly through the pipe by fluid pressure, an elongated tubular body, a packer adapted to be radially expanded into fluid tight engagement with said pipe, means controlling the expansibility of said packer, pipe engaging means adapted to be moved radially outward relative to said body, and an elongated rod movable upwardly within said body from depressed to projected positions to actuate both said packer control means and said pipe engaging means, a spring tending to thrust said rod upwardly, and a latch releasably holding said rod in depressed position, said latch being releasable by movement out of the lower end of said pipe.

8. In a well pipe plug adapted to be forced downwardly through the pipe by fluid pressure, a tubular body, a packer adapted to be radially expanded into fluid tight engagement with said pipe, and pipe engaging balls adapted to be moved radially outward within openings in said body into engaging position with said pipe to hold the plug against longitudinal movement therein.

9. In a well pipe plug adapted to be forced downwardly through the pipe by fluid pressure, an elongated tubular body, a packer adapted to be radially expanded into fluid tight engagement with said pipe, means controlling the expansibility of said packer and comprising a member normally surrounding and confining an expansible portion of said packer but movable relative to the packer to release said portion for expansion, pipe engaging means adapted to be moved radially outward relative to said body, and an elongated rod movable longitudinally within said body to actuate both said packer control means and said pipe engaging means.

10. In a well pipe plug adapted to be forced downwardly within the pipe by fluid pressure, the combination comprising a radially expansible packer, a member having a bore receiving and holding one end of said packer in radially constricted condition, said member being movable relative to said packer to release said end of the packer from said bore to permit expansion of said end, and means for so moving said member after the plug has been forced down into the well pipe and is unsupported from the ground surface excepting whatever support may be given the plug by engagement with said pipe.

11. In a well pipe plug adapted to be forced downwardly within the pipe by fluid pressure, the combination comprising a radially expansible packer, a member having a bore receiving and holding one end of said packer in radially constricted condition, yielding means urging said member into engagement with the packer, said member being movable relative to said packer to

release said end of the packer from said bore to permit expansion of said end, and means for so moving said member after the plug has been forced down into the well pipe and is unsupported from the ground surface excepting whatever support may be given the plug by engagement with said pipe.

12. In combination with a well pipe string comprising joined pipe sections and having downwardly facing internal shoulders at the joints, a plug adapted to be forced downwardly through the pipe string, a packer carried by the plug, pipe engaging means carried by said plug and movable from radially contracted to expanded positions, and means for positively expanding said pipe engaging means to arrest movement of the plug longitudinally within the pipe string, said plug being movable upwardly from any point between successive pipe joints and with said pipe engaging means in expanded position until the pipe engaging means engages the internal pipe string shoulder immediately above said engaging means.

13. In combination with a well pipe string comprising joined pipe sections and having downwardly facing internal shoulders at the joints, a plug adapted to be forced downwardly through the pipe string, a packer carried by the plug, pipe engaging means carried by said plug and movable from radially contracted to expanded positions, and means for expanding said pipe engaging means to arrest movement of the plug longitudinally within the pipe string, by virtue of movement of a lower portion of said plug out of the lower end of the pipe, said plug being movable upwardly from any point between successive pipe joints and with said pipe engaging means in expanded position until the pipe engaging means engages the internal pipe string shoulder immediately above said engaging means.

14. In combination with a well pipe string comprising joined standard pipe sections and having downwardly facing internal shoulders at the joints, a plug adapted to be forced downwardly through the pipe string, a packer carried by the plug, the length of said plug below the packer being in excess of the length of one of said pipe sections, pipe engaging means carried by said plug and movable from radially contracted to expanded positions, and means for expanding said pipe engaging means to arrest movement of the plug longitudinally within the pipe string, by virtue of movement of a lower portion of said plug out of the lower end of the pipe, said plug being movable upwardly from any point between successive pipe joints and with said pipe engaging means in expanded position until the pipe engaging means engages the internal shoulder immediately above said engaging means.

15. In combination with a well pipe string comprising a series of pipe stands each consisting of a pipe section connected at its upper end with a coupling having a reduced diameter bore and presenting within the pipe string a downwardly facing shoulder, a plug adapted to be forced downwardly within the pipe string, a packer carried by said plug, said packer being adapted to be inserted within the bore of one of said couplings by upward movement of the plug in the pipe string, and then to be expanded by the well pressure into fluid tight engagement with the coupling, and radially expansible means carried by the plug and adapted to engage the lower end of said packer receiving coupling to prevent further upward movement of the plug.

16. In combination with a well pipe string comprising a series of pipe stands each consisting of a pipe section connected at its upper end with a coupling having a reduced diameter bore and presenting within the pipe string a downwardly facing shoulder, a plug adapted to be forced downwardly within the pipe string, a packer carried by said plug, said packer being adapted to be inserted within the bore of one of said couplings by upward movement of the plug in the pipe string, and then to be expanded by the well pressure into fluid tight engagement with the coupling, and radially expansible pipe engaging means carried by said plug and adapted to engage the lower end of said packer containing coupling to prevent further upward movement of the plug.

17. In combination with a well pipe string comprising a series of pipe stands each consisting of a pipe section connected at its upper end with a coupling having a reduced diameter bore and presenting within the pipe string a downwardly facing shoulder, a plug adapted to be forced downwardly within the pipe string, a packer carried by said plug, releasable means acting normally to radially constrict said packer, said packer being adapted to be inserted within the bore of one of said couplings by upward movement of the plug in the pipe string and then to be expanded by the well pressure into fluid tight engagement with the coupling, and means for releasing said packer constricting means by virtue of movement of a lower portion of said plug out of the lower end of said pipe.

18. In combination with a well pipe string comprising a series of pipe stands each consisting of a pipe section connected at its upper end with a coupling having a reduced diameter bore and presenting within the pipe string a downwardly facing shoulder, a plug adapted to be forced downwardly within the pipe string, a packer carried by said plug, said packer being adapted to be inserted within the bore of one of said couplings by upward movement of the plug in the pipe string, and then to be expanded by the well pressure into fluid tight engagement with the coupling, radially expansible pipe engaging means carried by said plug and adapted to engage the lower end of said packer containing coupling to prevent further upward movement of the plug, and means for actuating said pipe engaging means by virtue of movement of a lower portion of said plug out of the lower end of said pipe.

19. In combination with a well pipe string comprising a series of pipe stands each consisting of a pipe section connected at its upper end with a coupling having a reduced diameter bore and presenting within the pipe string a downwardly facing shoulder, a plug adapted to be forced downwardly within the pipe string by fluid pressure, a packer carried by said plug, releasable means acting normally to radially constrict said packer, said packer being adapted to be inserted within the bore of one of said couplings by upward movement of the plug in the pipe string and then to be expanded by the well pressure into fluid tight engagement with the coupling, and means for releasing said packer constricting means by virtue of movement of a lower portion of said plug out of the lower end of said pipe, the length of said plug below the packer being in excess of the length of one of said pipe stands.

20. In combination with well tubing comprising pipe sections connected by a coupling forming at its lower end a downwardly facing shoulder and having a bore smaller than the pipe bore, a plug

- comprising a radially expandible packer, radially expandible pipe engaging means directly below the packer and movable downwardly through the coupling bore, and means for positively expanding 5 said pipe engaging means, the pipe engaging means being adapted to engage the lower end of the coupling with said packer inserted in the packing bore above, to arrest upward movement of the plug.
- 10 21. In combination with well tubing comprising pipe sections connected by a coupling forming at its lower end a downwardly facing shoulder and having a bore smaller than the pipe bore, a plug comprising a mandrel, a packer sleeve surrounding the mandrel and expandible by movement longitudinally thereof, radially expandible pipe engaging means directly below the packer and movable downwardly through the coupling bore, and means for positively expanding said 15 pipe engaging means, the pipe engaging means being adapted to engage the lower end of the coupling with said packer inserted in the packing bore above, to arrest upward movement of the plug.
- 20 22. A well pipe plug comprising a body, radially expandible pipe engaging means carried by the body, a radially expandible packer mounted on the body, means for controlling the expansion of said pipe engaging means, and a sleeve surrounding the body and releasably holding the last mentioned means against movement to cause the pipe engaging means to expand, said plug being downwardly movable through and separable from the sleeve to release said control means.
- 25 23. A well pipe plug comprising a body, radially expandible pipe engaging means carried by the body, a radially expandible packer mounted on the body, means for radially expanding said pipe engaging means, and a sleeve surrounding the body and releasably holding the last mentioned means against movement to expand the pipe engaging means, said body and the packer and pipe engaging means being movable downwardly through and out of said sleeve to release the pipe engaging means for expansion and to free the plug from the sleeve.
- 30 24. In a plug adapted to be moved downwardly through a well pipe, a packer adapted to be expanded radially into fluid tight engagement with said pipe, control means maintaining said packer in radially constricted condition during downward passage of the plug in said pipe, and means located at a lower portion of the plug and controlled by engagement with the pipe, the last mentioned means operating upon its movement out of the lower end of the pipe, to actuate said packer control means to cause said packer to expand within said pipe at a point above its lower end.
- 35 25. In a plug adapted to be moved downwardly through a well pipe, a packer adapted to be expanded radially into fluid tight engagement with said pipe, means for releasably holding said packer in radially constricted condition during downward passage of the plug in said pipe, and means normally engaging the pipe and actuated by virtue of its movement out of the lower end of the pipe, for releasing said holding means to permit the packer to expand radially within the pipe.
- 40 26. In a plug adapted to be moved downwardly through a well pipe, a packer adapted to be ex-

panded radially into fluid tight engagement with said pipe, control means maintaining said packer in radially constricted condition during downward passage of the plug in said pipe, and means including a latch device carried by the plug below the packer and operable by movement out of the lower end of the pipe to actuate said packer control means and to cause the packer to expand within said pipe at a point above its lower end. 5

27. A plug adapted to be moved downwardly through a well pipe that is open at its lower end, said plug comprising radially movable means adapted to engage the inside of said pipe to hold the plug against upward movement therein, means normally engaging the pipe and actuated by virtue of movement out of the lower end of the pipe, for radially expanding said holding means within the pipe at a point above its lower end, and a packer having a depending lip portion expandible into tight engagement with the well pipe by upwardly applied fluid pressure. 10

28. A plug adapted to be moved downwardly through a well pipe that is open at its lower end, said plug comprising radially movable means adapted to engage the inside of said pipe to hold the plug against upward movement therein, means for radially expanding said engaging means within the pipe at a point above its lower end, the last mentioned means comprising a member movable relative to said pipe engaging means, and normally engaging the pipe and located at the lower portion of the plug, the last mentioned means being operable by movement out of the lower end of the pipe to expand the pipe engaging means, and a packer having a depending lip portion expandible into tight engagement with the well pipe by upwardly applied fluid pressure. 25

29. A well pipe plug adapted to be dropped or forced downwardly by fluid pressure within a well pipe, said plug including a body, radially expandible pipe engaging means carried by the body, yielding means for expanding said pipe engaging means, holding means for releasably maintaining said pipe engaging means in contracted position when the pipe engaging means is out of the pipe, and control means normally engaging the pipe bore wall and operable by movement out of the lower end of the pipe to expand said pipe engaging means within the pipe, 40 said holding means being releasable after the pipe engaging means is inserted within the pipe to permit expansion of the pipe engaging means upon movement of the control means out of the lower end of the pipe. 45

30. A well pipe plug adapted to be dropped or forced downwardly by fluid pressure within a well pipe, said plug including a body, a radially expandible packer carried by the body, means for expanding the packer, holding means for releasably maintaining the packer in contracted condition when the pipe engaging means is out of the pipe, and control means normally engaging the pipe bore wall and operable by movement out of the lower end of the pipe to release said packer for radial expansion within the pipe, said holding means being releasable after the packer is inserted within the pipe to permit expansion of the packer upon movement of the control means out of the lower end of the pipe. 55
